(No Model.)

H. HUGHES.
COVERING FOR CABLE CONDUITS.

No. 462,135.

Patented Oct. 27, 1891.

UNITED STATES PATENT OFFICE.

HARRY HUGHES, OF ABILENE, KANSAS.

COVERING FOR CABLE-CONDUITS.

SPECIFICATION forming part of Letters Patent No. 462,135, dated October 27, 1891.

Application filed April 23, 1891. Serial No. 390,110. (No model.)

To all whom it may concern:

Be it known that I, HARRY HUGHES, of Abilene, in the county of Dickinson and State of Kansas, have invented a new and Improved 5 Covering for Cable-Conduits, of which the following is a full, clear, and exact description.

The object of the invention is to provide a new and improved covering which is simple and durable in construction, arranged to be opened by the pilot of the car, and adapted to be automatically closed by the same after the grip has passed.

The invention consists of a series of plates 15 fitted to slide in angular bearings across the slot, and levers, each connected by a link with a plate and extending in the path of the pilot at the next following plate.

The invention also consists of certain parts 20 and details and combinations of the same, as will be described hereinafter, and then pointed out in the claims.

Reference is to be had to the accompanying drawings, forming a part of this specification, 25 in which similar letters of reference indicate corresponding parts in all the figures.

Figure 1 is a plan view of the improvement with parts removed and parts in section. Fig. 2 is a like view of the same in a different position. Fig. 3 is a sectional side elevation of the same. Fig. 4 is a transverse section of the same on the line $x-x$ of Fig. 3, and Fig. 5 is a detail perspective view of two adjacent sliding plates.

35 The cable-conduit A, of any approved construction, is provided in its top with the usual slot B, adapted to be covered by a series of plates C C' C² C³, &c., arranged one in front of the other and fitted to slide transversely in a 40 recess D, formed on top of the conduit A at one side of the slot B, as is plainly illustrated in the drawings. The recess D is adapted to be closed on top by suitable covering-plates E, resting on the rabbets at the sides of the said 45 recess.

Each of the plates C C' C² C³, &c., is fitted to slide in bearings F, fixed in the recess D and arranged angularly to the slot, as is plainly illustrated in Figs. 1 and 2. The bearings F 50 extend into angular recesses or grooves F' in the said plate C C', &c., so that the said plates in their transverse movement slide an-

gularly to open and close the slot B. The ends G and G' of each plate are arranged at angles to the bearings F, the front end G of each plate being provided on its outermost corner with a square offset G² for a purpose hereinafter more fully described. This square offset G² extends under a corresponding recess or notch in the end G' of the preceding plate, as clearly shown in Figs 3 and 5, so that the plates can readily open and close without being hindered by the said offset G².

Each of the plates C C' C², &c., is connected at its rear end G' with a link H, extending under the next following plate and pivotally connected with a lever I, fulerumed at I' to the bottom of the recess D, as is plainly illustrated in Fig. 4. The front end I² of the lever I extends into the slot B and is adapted 70 to be engaged by a pilot J, secured to the under side of the car K in front of the grip L.

The operation is as follows: The several plates C C' C² C³, &c., in their normal position close the slot D, and when the car K 75 travels forward in the direction of the arrow a' the pilot J engages the first plate C at the projection G² of the front corner, so that a pressure is exerted on this plate, which is thereby caused to slide transversely in its angular bearings F. This movement of the plate opens the slot for the passage of the grip L, and the plate thus opened remains open for a short time—that is, until the pilot J has opened in a similar manner the next 80 following plate and travels a little past the middle of the said plate, when it engages the projecting end I² of the lever I, so that the latter receives a swinging motion in the direction of the arrow b', whereby the link H 90 is pushed backward, thereby causing the plate C first opened to slide transversely to its former position, so as to close the slot B. This operation is repeated with the successive plates—that is, a preceding plate is closed 95 when the pilot J has traveled to about the middle of the following plate, at which the lever I, operating the preceding plate, is engaged and actuated by the pilot J. Thus it will be seen that the slot B remains closed at all times after the car has passed, so as to prevent injury to animals or vehicles by being caught in the said slot B. The pilot J is preferably held detachably on the car K, so that

100

it can be moved to either side of the grip L whenever the car is turned or travels on the return trip. It will further be seen that no springs whatever are required for accomplishing the movement of the plates C, &c., the latter being actuated by direct and positive mechanism.

Having thus described my invention, what I claim as new, and desire to secure by Letters 10 Patent, is—

1. A covering for cable-conduits, provided with a series of plates fitted to slide in angular bearings across the conduit-slot, the said plates being opened and closed by a pilot 15 held on the car, substantially as shown and described.

2. In a covering for cable-conduits, the combination, with a series of horizontally-sliding plates adapted to be moved from over the 20 slot of the conduit by a pilot on the car engaging the plates, of levers connected with said plates for engagement with the pilot for moving the plates across said slot, substantially as described.

25 3. In a covering for cable-conduits, the com-

bination, with a series of plates, of angular bearings in which the said plates are fitted to slide to open and close the conduit-slot, a link pivotally connected with a plate at the rear end, and a lever pivotally connected with the 30 said link and extending at its free end into the conduit-slot in the path of a pilot on the car, substantially as shown and described.

4. In a covering for cable-conduits, the combination, with fixed angular bearings, of a 35 series of plates fitted to slide in the said angular bearings to open and close the conduit-slot, each plate being formed with angular ends, a link pivotally connected with the rear end of each plate, and a lever pivotally connected with each link and arranged under the next following plate and having its free end extended into the conduit-slot to be engaged by a pilot on the car to close the preceding plate, substantially as shown and described. 40 45

HARRY HUGHES.
